UNITED STATES PATENT OFFICE.

SEYMOUR C. PALMER, OF SOUTH NORWALK, CONNECTICUT, ASSIGNOR, BY DIRECT AND MESNE ASSIGNMENTS, TO ELLEN M. PALMER AND ALDEN SOLMANS, OF SAME PLACE.

HAT-FORMING MACHINE.

SPECIFICATION forming part of Letters Patent No. 399,551, dated March 12, 1889.

Application filed September 24, 1888. Serial No. 236,147. (No model.)

To all whom it may concern:

Be it known that I, SEYMOUR C. PALMER, a citizen of the United States, residing at South Norwalk, in the county of Fairfield 5 and State of Connecticut, have invented certain new and useful Improvements in Hat-Dipping Apparatus for Hat-Forming Machines; and I do hereby declare the following to be a full, clear, and exact description of 10 the invention, such as will enable others skilled in the art to which it appertains to make and use the same.

My invention has reference to certain improvements in hat-forming machines; but 15 especially appertains to an apparatus for dipping hat-bodies while on the cone.

The object of this invention is to accomplish the dipping of the hat-bodies automatically by mechanical means, while at the same 20 time the speed at which the hat is dipped is variable; and with these ends in view my invention consists in the details of construction and combination of elements hereinafter set forth and then specifically designated by the 25 claims.

In order that those skilled in the art to which my invention appertains may understand how to make and use the same, I will proceed to describe its construction and operation in detail, referring by letter to the accompanying drawings, forming a part of this specification, in which—

Figure 1 is a side elevation of my improvement; Fig. 2, a front elevation, the plunger-rod being broken away; and Figs. 3, 4, and 5 35 are detail detached views showing the relative positions of the crank and reciprocating lever during the operation of submerging the hat-body.

Similar letters denote like parts in the several figures.

A is the tub containing water within which the hat-body A' is to be dipped, and B are guide-lugs projecting from said tub.

C is the platform on which the cone is placed, and D is a bail secured at the ends to the platform and passed through the lugs B, for the purpose of guiding and steadying the platform during the operation of dipping.

E E' are hangers, and F is a counter-shaft journaled within said hangers.

G is a pulley loose on said shaft and having a hub, H, within which latter are formed notches a.

I is a disk rigid on said shaft, and J is a 55 bolt extending loosely through said disk and adapted to be thrown within the notches a, as will be presently explained. A spring, b, secured to said disk and bearing against the rear of said bolt, tends to shoot the latter forward. 60

K is an arm secured to the hanger E', and L is a detent pivoted to said arm and sustained in elevation by a coil-spring, c, attached at its extremities to said arm and detent. The nose of said detent is beveled, as 65 seen at d, and is within the field of travel of the heel end of the bolt J, so that when the said heel end is carried against the beveled nose the bolt will be withdrawn against the resiliency of the spring b, and the said heel 70 will be arrested by the stop-lug e at the base of the beveled nose.

M is a crank rigidly secured on the shaft F.

N is a lever pivoted at the rear end to a hanger, O, and P is a rigid rod pivoted at its 75 extremities to the forward end of the lever N and the top of the bail, respectively.

Q is a slot within the body of the lever N, and within this slot travels the pin R of the crank M, so that it will be clearly seen that 80 motion is communicated to the rod P from the crank M through the intermediate lever, N. The contour and extension of the slot Q are such with respect to the line of travel of the crank-pin that a vertical reciprocation of 85 variable speed will be imparted to the lever according to the angles which said slot assumes to said line of travel during the circuit of the crank-pin. Thus at Fig. 1 this angle will be seen to be very steep, and therefore the lever 90

will be carried downward at a very fast rate when the crank is revolved in the direction indicated by the arrow until the position at Fig. 3 is reached, when that part of the slot in the immediate path of the pin is nearly 95 parallel with the line of travel of the pin, and the movement of the lever will therefore be continued at a much slower speed until the position shown at Fig. 4 is reached, where the said slot coincides with the line of travel of 100 said pin throughout an arc of about sixty degrees, the result of this being of course that

the lever has no movement during the traversing of said arc.

The diagram at Fig. 5 shows the relative position of the crank, pin, and slot when the pin has reached the end of said arc and immediately prior to the elevation of the lever by the return movement of said crank.

Hat-bodies are at present dipped by hand, the hat being transferred on the forming-cone 10 directly to the dipping-tub, the combined operation of forming and dipping requiring the service of an extra man on every forming-machine.

By the use of my improvement a single operator removes the cone with the hat thereon 15 from the forming-machine, places said cone on the platform C, pulls the cord S, attached to the detent L, thereby releasing the bolt J and effecting an engagement between the latter and the notched hub H, whereby the crank and lever are operated to lower said platform to submerge the hat, and returning to the forming-machine places another cone therein and superintends the initial formation of another hat-body. He then slips the first hat 20 (which has in the meantime been dipped) from its cone, and the second hat having by this time been formed, he removes the same on its cone from the forming-machine; and 25 after placing the last-mentioned hat on the dipping-platform he places the first cone back in the forming-machine, and after superintending the initial formation of a third hat slips the second hat, which has in the meantime been dipped, from its cone, and so forth. It will thus be seen that a single operator attends continuously to both the forming and dipping of the hat-bodies.

It is all important that the hat should be 30 submerged at a speed which gradually decreases as the water continues to rise within the cone, for the reason that the air becomes so compressed within the cone that the speed of dipping must be so regulated as to allow 35 the compressed air to escape gradually through the hat-body, otherwise the hat-tip will be blown out or so distorted as to render the hat worthless. When the hub H is clutched by the bolt J, on the release of the latter by pulling the cord S, the shaft F will 40 only revolve once, since the bolt on the completion of its circuit will strike against the inclined nose of the detent L, and thereby be withdrawn from the notched hub and arrested in its movement by the stop e, as hereinbefore set forth, thus bringing the crank to 45 a normal position at rest, and causing the

platform C to remain in elevated position, as shown at Fig. 1.

In order that the action of the water and air within the cone during the process of submerging may be uniform in all instances, it is important that there should be a positive movement to the platform, and therefore a rigid connection is necessary between the lever N and said platform, and the rod P constitutes a salient part of my invention.

The operation of the crank-pin within the slotted lever of course renders the lever capable only of a limited variable motion, for the reason that during the fastest and slowest movements of the lever the said pin travels in opposite directions within the same section of the slot. While this construction is admirably adapted for forming comparatively fine grades of hats, still in order to form the finest grades, it is necessary that the operation of dipping should not be effected by a limited variable motion, and I have accordingly shown and described in my pending application, Serial No. 287,184, filed October 4, 1888, a construction in which a face-cam is used instead of the cam-slotted lever, in order that there shall be no limit to the fastest and slowest movements in the operation of dipping the hats.

Having thus described my invention, what I claim as new, and desire to secure by Letters Patent, is—

1. In a hat-dipping apparatus, the combination, with a crank, of a pivoted lever having a slot within which the pin of said crank extends, and the cone-supporting platform suspended from the forward end of said lever, substantially as set forth.

2. The combination, with a revolving crank and a pivoted lever having a slot within which the crank-pin travels during its circuit, of a rod pivotally hung from the end of said lever, and the cone-supporting platform suspended from the rod, substantially as set forth.

3. In combination with the reciprocatory lever and the bail of the cone-supporting platform, the rigid rod connecting said bail and lever, whereby a positive and synchronous movement is imparted from the latter to the former, substantially as set forth.

In testimony whereof I affix my signature in presence of two witnesses.

SEYMOUR C. PALMER.
